UNITED STATES PATENT OFFICE

LYMAN C. HUFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

DEPHLEGMATOR

Application filed October 4, 1922, Serial No. 592,194. Renewed December 26, 1928.

This invention relates to improvements in dephlegmator fractionating columns or reflux condensers and refers more particularly to a vertical heat interchanger and partial vapor or reflux condenser, which is adapted for use particularly in the art of cracking hydrocarbon oils to produce maximum yields of light hydrocarbon products suitable for gasoline and the like.

10 Among the objects of the invention are to provide a dephlegmator divided into two parts, in the lower portion of which are placed a series of vertically extending baffles, so constructed that the rounded end of one 15 baffle will overlap the rounded end of the next baffle in a vertical plane; to provide a construction in which the arrangement just described permits of a maximum vaporizing surface within the shell; to provide a construction in the upper part of which is positioned a spiral coil extending downwardly through which distillate of a predetermined gravity may be forced; to provide a construction 20 of the character described in which a series of fins, placed one over the other, are positioned above and within the spiral coil heretofore described; to provide a dephlegmator which has inlet and outlet vapor pipes, distillate and raw oil inlets so controlled that 25 predetermined quantities can be forced to the dephlegmator; to provide a construction of the character described, which permits of a continuous thin film of oil flowing downwardly over the vertical baffles, obviating the 30 bubbling commonly produced in a dephlegmator in which the vaporization zone is limited, and in general to provide improvements of the character referred to.

35 The single figure in the drawing is a view of 40 a dephlegmator, equipped with my invention, partly in side elevation, and partly in vertical cross section.

Referring in detail to the drawing, 1 designates the dephlegmator as a whole, which 45 may take the form of a vertical steel shell. This vertical shell may be constructed in one piece having a top portion 2, bottom portion 3, and side wall 4, or it may be constructed as shown in the drawing in such a manner as to 50 provide a top piece 5, bolted as shown at 6.

In the bottom portion of the shell are positioned a series of vertically extending baffles 7, which may be constructed of sheet metal, aluminum, etc. These baffles are preferably staggered in form as shown having rounded ends 8, the rounded end of one baffle overlapping the rounded end of a similar baffle in a vertical plane. These baffles are supported in the dephlegmator by means of the lugs 9, and bottom cross members 10, tied together by bolts and spacers 10a, extending through the baffles. 11 designates a raw oil inlet pipe, from any extraneous source of supply, which pipe is preferably circular in form, conforming to the inner periphery of the shell. It is provided with a series of nozzles 12, by means of which the oil is caused to be forced out of the pipe in a uniform spray. 14 designates a distillate inlet line, which terminates in a downwardly extending continuous helical pipe in the form of a coil 15, terminating in an upturned pipe 16. The pipe 16 leads upward and terminates in the outlet 18. A cap 19 is provided over the outlet 18, held in place by suitable lugs (not shown). I provide a series of projecting fins 19a extending around the pipe 16, which in the present instance, are practically oval-shaped in cross section.

In the cracking of hydrocarbon oils, under heat and pressure, the dephlegmator performs a double function which is well known and need not be explained in detail. The vapors, heated above their conversion temperature, are introduced through the vapor inlet 20 in the bottom portion of the dephlegmator beneath the lower end of the vertical staggered baffles 7. Being under pressure, the vapors are forced upward through the spaces formed between the baffles 7. Cold distillate of a predetermined gravity may be continuously introduced into the system through the pipe 14, flowing downwardly as explained through the pipe 15, then upwardly through the pipe 16. During the travel of the distillate, which may be introduced at atmospheric temperature, it is heated by the vapors passing upward around the pipes 15 and 16, and when it leaves the outlet 18, it is substantially at a conversion temperature. Upon release therefrom, the lighter fractions

will vaporize, while the residue will flow in a thin even film down the sides of the fins 19a, continuously vaporizing. These fins may consist of plain or corrugated surfaces, which 5 slope on an angle so as to retard the flow of liquid over them and retain the heated liquid in this zone for a maximum period of time in contact with the surrounding hot vapors.

Raw oil may be introduced into the system 10 through the inlet pipe 11 and sprayed over the baffles where it will be preheated by the vapors and will mix with the reflux or condensate from the condensed vapors and may be drawn off from the bottom connection and 15 conveyed to the heating tubes for further treatment. Vapors are withdrawn from the dephlegmator through the vapor outlet-pipe 21 leading to any suitable condensing and collecting means. The vapors which condense in 20 their upward passage through the dephlegmator will fall back as reflux condensate and will flow downwardly on the surfaces of the baffles 7.

As one of the features of my invention, I 25 wish to point out that the condensate or raw oil flowing down over the surface of the baffle plates in a thin even film, will be retarded and allowed a maximum period of time for the lighter ends to vaporize. The vapors 30 flowing upwardly are continuously baffled against the sloping surfaces of the vertical baffle plates, which are covered with a descending film of reflux, causing a scrubbing action of the vapors. Any moisture or globules of oil carried in suspension in the vapors 35 will be deposited with the reflux condensate on the surface of the plates and intimately mixed therewith. After the reflux condensate has been subjected for a maximum 40 period of time to the action of the incoming heated vapors, the still unvaporized portion will be drawn off through the drawoff pipe 22 to any suitable storage or returned for re-treatment in the same system.

45 The entire outer wall of the dephlegmator may be lagged to prevent the radiation of heat or it may be desirable to only lag part of the side wall, for instance, the bottom half. The surface of the baffle plates may be corrugated or rigid, if desired, to further retard 50 the flow of liquid thereon. The baffles are so spaced that any condensate from the vapors or reflux will fall but a short distance before coming in contact with some portion 55 of the baffles. It will be understood that the temperature of the vapors leaving the dephlegmator through the outlet 21 can be readily controlled and regulated by the amount of cooling liquid introduced through 60 the pipe 14.

I do not wish to restrict myself to the use of my invention for the cracking of hydro-carbon oils. It may be used with slight modifications as a distilling apparatus for distilling alcohol. In addition, with slight

modifications, it may be used as a topping still for the purpose of fractionating and recovering the light fractions of oil, commonly called "topping" in the art. For instance, a vertical still can be equipped with 70 my vertically extending staggered baffles positioned therein. The crude oil may be introduced at the top of the still or at a point above the baffles, and allowed to flow down over the zig zag surfaces of said baffles. 75 Steam under pressure may be forced upward continuously from the bottom of the still, and when this steam meets the descending film of oil, some of its heat will be transferred thereto and part of the light constituents of the oil will vaporize, which together with the steam which does not condense, may be drawn off to a suitable condensing and separating means. The unvaporized portion will flow downwardly and may be withdrawn. 80

Further, the crude oil may be heated and partially vaporized in the usual way, and the vapors introduced into the still below the vertically extending staggered baffles and 90 the vapors forced upward as explained. The unvaporized portion of the heated crude oil can be separated from the vapors in a separate still or tank interposed between the heating means and still and drawn off while 95 the vapors only are made to enter the still below the staggered baffles.

It will be seen from the foregoing description that the staggered baffles allow of maximum cross sectional vapor space through the 100 dephlegmator, insuring slow velocity of vapors and permitting the use of small diameter dephlegmator. Also these staggered baffles are self-cleaning and cannot become clogged with foreign matter, as there are no 105 flat surfaces on which foreign matter can collect. By heating distillate in a closed coil as explained and discharging it in the upper part of dephlegmator, and allowing it to flow over the series of fins where it is 110 exposed in a thin film to the hot vapors, it readily absorbs its heat of vaporization and vaporizes, thus cooling the surrounding vapors, and passes out of the dephlegmator with vapors which have been cooled by reason of the vaporization. 115

It is obvious that the coil and fins in the upper portion of the dephlegmator or still may be replaced with a series of vertically extending baffles similar in construction to those in the lower part of the apparatus and that the cooling distillate may be introduced by means of a spray on the top of baffles where it will be heated and vaporized by the ascending vapors as it flows downward in a 120 thin film over the baffles.

I claim as my invention:

1. An apparatus of the character described, comprising an elongated vertical shell, means for introducing vapors into the

- lower portion of said shell, a plurality of staggeredly disposed baffles positioned within the lower portion of said shell to initially retard the flow of vapors therethrough,
- 5 means for conveying a cooling medium downwardly through a substantial portion of said shell in indirect contact with the vapors, means for returning such cooling medium to the upper portion of said shell and
- 10 means for then causing such cooling medium to flow downwardly through the shell in direct contact with the vapors and means for taking off uncondensed vapors from said shell.
- 15 2. An apparatus of the character described comprising an elongated vertical shell, means for introducing vapors into the lower portion of said shell, means for conveying a cooling medium downwardly
- 20 through a substantial portion of said shell in indirect contact with the vapors, means within the shell for returning such cooling medium to the upper portion of said shell and means for then causing such cooling
- 25 medium to flow downwardly through the shell in direct contact with the vapors and means for taking off uncondensed vapors from said shell.
